ATTYS.

UNITED STATES PATENT OFFICE.

JAMES H. BALLARD, OF MAPLEWOOD, MISSOURI, ASSIGNOR TO CRADDOCK TERRY COMPANY, OF LYNCHBURG, VIRGINIA, A CORPORATION OF VIRGINIA.

SHOE.

Application filed September 19, 1924. Serial No. 738,695.

To all whom it may concern:

Be it known that I, JAMES H. BALLARD, a citizen of the United States, residing at Maplewood, Missouri, have invented a certain new and useful Improvement in Shoes, of which the following is a specification, such as will enable others skilled in the art to which it appertains to make and use the same.

10 My invention relates to shoes and consists in a novel shoe sole structure.

The main object of my invention is to improve the appearance of a shoe by reducing the thickness of the edge of the sole without 15 eliminating certain steps in manufacturing which have a tendency to thicken the edge of the sole and without affecting the quality of the sole from the standpoint of durability.

20 My invention is particularly adapted to be applied to a stitch-down shoe, the lasting operation in which requires the use of a so-called middle sole which heretofore has contributed to the thickness of the edge of the 25 shoe sole but in my improved shoe is so shaped along its edge that the latter is not apparent in the completed shoe.

These general objects and other detail objects as will appear from an inspection of 30 my disclosure are secured by the method and product described below and illustrated in the accompanying drawings, in which—

Figure 1 is a side elevation of a portion of a rough-rounding machine adapted to also 35 bevel the edge of the middle sole during the rough-rounding operation and in this drawing a section through a shoe being operated upon is indicated.

Figure 2 is a front elevation of the tool 40 used to bevel the middle sole.

Figure 3 is a transverse section through the vamp of a shoe and last before the same is operated upon by the machine illustrated in Figure 1.

45 Figure 4 is a similar section after the operation.

Figure 5 is a similar section after the outer sole has been stitched to the shoe.

50 Figure 6 is a side elevation of the completed shoe.

In the drawings, 1 indicates the last and 2 the upper of a shoe drawn over the last and turned outwardly at 3 where it is stapled or otherwise secured to a light middle sole 4

55 at the end of the lasting operations. It is to be understood that the upper may be provided with a lining and with suitable reinforcing pieces, if desired, the same being omitted from the drawings to avoid confusion.

60 After the application of the middle sole to the upper during the lasting operation, the shoe is passed through the machine indicated in Figure 1, the guide 5 engaging the vertical side of the upper 65 and determining the width of the out-turned portion in the completed shoe. It will be understood that the knife 6 reciprocates in the usual manner and cuts through the middle sole and upper to form 70 the contour of the sole as the latter is fed through the machine. At the side of knife 6 is the beveling knife 7 set in a block 8 which forms a support for the middle sole as it moves past knife 7. The middle sole 75 and the out-turned portion 3 of the upper are held against block 8 by the vertical face of guide 5 and it will be understood that the parts referred to are provided with any ordinary adjusting screws or other adjusting elements so that, as the shoe leaves the machine, the edge of the middle sole is beveled 80 from a point adjacent the staples 9 to a feather edge adjacent the outer edge of upper portion 3 produced by the rough-rounding knife 6.

85 In passing the shoe through the rough-rounding and beveling machine, the operation will be started at a point adjacent the shoe heel and will proceed therefrom forwardly to the front of the shoe and rearwardly to a similar point adjacent the heel on the opposite side of the shoe so that only the shank, sole and toe portions of the middle sole are beveled, leaving the heel portion 90 of uniform thickness at its edge. The beveled portion will merge into the untouched or square portion adjacent the front of the heel.

95 After the above described operation, the welt 10 and outer sole 11 will be stitched to the upper and middle sole in the usual manner and the pressure applied during this operation will bring together the edges of the welt, upper portion 3 and outer sole and 100 smooth the same so as to produce an edge of the completed sole in which the normal thickness of the middle sole 4 has been eliminated 105

as the feather edge of the middle sole will not be apparent to the eye of the observer.

In Figure 6, illustrating the complete sole, I show lines indicating the meeting edges of the welt and the upper and the upper and the sole, but it will be understood that these lines are not obvious in the shoe as manufactured due to the smoothing operation of the shoe stitcher and to the application of blacking or enamel to the edge of the completed sole.

As middle soles used in shoes of this type vary from two and one-half to four irons in thickness and as the total thickness of a shoe sole is about twelve or fifteen irons, it is obvious that the reduction in thickness of the edge of the shoe sole is about twenty per cent. This reduction produces a marked improvement in the neat appearance of the sole which improvement is especially desirable in the production of foot wear for ladies and children.

While I have shown and described my invention as applied to a stitch-down shoe, it is obvious that the same may be applied to other types of shoes and I contemplate the use of my invention on all kinds of footwear irrespective of the method of manufacture or of the details involved in addition to the features described. Obviously, modifications in the method of manufacture may be made without affecting the finished product and I contemplate the inclusion of any variations in the method or shoe as are included in the scope of my invention as expressed in the appended claims.

I claim:

1. In a shoe, an upper, a middle sole having a beveled edge, means securing said upper to said middle sole, an outer sole, and

additional means for securing said middle sole to said outer sole.

2. In a shoe, an upper, a middle sole having a beveled edge, means securing said upper to said middle sole, a welt, an outer sole, and additional means securing said middle sole to said outer sole and welt.

3. In a shoe, a middle sole of substantially uniform thickness throughout nearly all its width but having a beveled edge, an upper with its marginal portion turned outwardly and secured to said middle sole inside of the beveled portion of the latter, and an outer sole secured to said upper and the beveled portion of said middle sole.

4. In a stitch-down shoe, a middle sole beveled to provide a feather edge, an upper with its marginal portion turned outwardly, securing elements through said middle sole and upper, an outer sole, a welt, and additional securing elements through said welt, upper, middle sole, and outer sole.

5. In a stitch-down shoe, a middle sole beveled to provide a feather edge, an upper with its marginal portion turned outwardly, securing elements through said upper and the unbeveled portion of said middle sole, a welt, and additional securing elements through said welt, upper, outer sole, and the beveled portion of said middle sole.

6. In a shoe, an intermediate sole extending full length of the shoe and having a beveled edge extending throughout the sole and shank portion and merging into a square edge extending throughout the heel portion.

In testimony whereof I hereunto affix my signature this 16th day of September, 1924.

JAMES H. BALLARD.
